ENGINE STARTER

Filed July 18, 1928

UNITED STATES PATENT OFFICE

PERRY E. MACK, OF MILWAUKEE, WISCONSIN, ASSIGNOR TO BRIGGS AND STRATTON CORPORATION, OF MILWAUKEE, WISCONSIN, A CORPORATION OF DELAWARE

ENGINE STARTER

Application filed July 18, 1928. Serial No. 293,721.

This invention relates particularly to starting devices for gas engines and the like and has as an object the provision of means for efficiently and quickly starting an engine which is actuated by depressing a foot lever which is movable to lie close to the engine when not in use.

Another object of this invention resides in the provision of a device of the character described having means releasing its connection with the engine the instant of its starting.

A further object of this invention resides in the provision of a device of the character described having an automatic clutch which is actuated to inoperative position by centrifugal force.

A still further object of this invention resides in the provision of a starting device of the character described having a sprocket wheel adapted to be driven by a chain upon movement of a foot lever, the chain disengaging the wheel when in inactive position.

And a more specific object of this invention resides in the provision of a clutch carried by the engine shaft and rotatable by a chain actuated by a starting lever, the chain being retracted by spring means.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is an elevational view of a portion of a gasoline engine illustrating my improved starting mechanism applied thereto, parts being broken away and in section to illustrate structural details;

Figure 2 is a sectional view taken through Figure 1 on the plane of the line 2—2;

Figure 3 is a cross sectional view taken through Figure 2 on the plane of the line 3—3, and illustrating the construction of the clutch mechanism; and

Figure 4 is a sectional view, taken through Figure 1 on the plane of the line 4—4.

Referring now more particularly to the accompanying drawing, in which like numerals designate like parts throughout the several views, the numeral 5 represents the base of a gasoline engine having a shaft 6 which may be the main crank shaft having a fly-wheel 7 mounted thereon. The fly-wheel is preferably provided with a tapered bore 9 in which the correspondingly tapered end 10 of the shaft 6 is positioned, being secured on the shaft by a special nut 11 and enclosed by a suitable guard or housing 8, secured to the engine frame.

The nut 11 has a stud 12 extended therefrom which provides the bearing for a ratchet device 13 and has its inner end internally threaded to receive the threaded end 14 of the shaft. Impinged between the inner face of the ratchet device 13 and the adjacent face of the fly-wheel 7 is a back plate 15 of a ratchet housing 16, the back plate 15 being provided with a central aperture to receive the end 14 of the shaft, as will be readily apparent.

The ratchet device 13 is freely pivoted on the stud 12 of nut 11 and is restrained against longitudinal movement thereon by the back plate 15 at one end and an enlargement 17 formed adjacent the outer end of the nut. The ratchet housing 16 mounts a pair of pawls 18 which are positioned between the back plate 15 and an outer plate 19 by rivets 20 or studs 20 extended through the plates 19 and 15 and the pawls 18. Springs 21 coiled about rivets 22 between the plates 19 and 15 normally urge the pawls inwardly to engage their hooked ends 23 with the teeth 24 of the ratchet device 13, the springs 21 being of such strength as to become inactive as soon as the engine starts running due to centrifugal force imposed on the outer free ends of the pawls.

A sprocket wheel 25 is formed on the outer

end of the ratchet device 13 with which a sprocket chain 26 is adapted to mesh to impart rotation to the ratchet device upon actuation of a foot pedal 27. The pedal 27 is hingedly connected at its inner end by a stud or pin 28 to a lever arm 29, having a stop 30 which abuts another stop 31 extended from the lever or lever arm 29 to limit clockwise movement of the pedal with respect to the lever arm. The inner end of the lever arm 29 is fixed on a shaft 32 journaled in suitable bearings, not shown, in the base 5 of the engine; and the outer free end thereof is curved to substantially goose-neck shape and has one end of the sprocket chain 26 connected thereto, as at 33.

The other end of the chain is connected with a wheel member 34 to wind thereon, the wheel member being freely pivotally mounted on the outer end of shaft 32 and consisting of a cup-shaped member 37 having an annular peripheral flange 38. An inner disc 39 riveted to the side of the cup-shaped member opposite its annular flange cooperates therewith to provide an annular recess or channel in which the chain is wound and unwound, the end of the chain being connected with the wheel by a stud 40 passing through the flange 38 and disc 39.

A coil spring 41 is positioned within the cup-shaped wheel member 34 and has one end secured to the wheel by being engaged over an instruck hook 42 and its other end secured in a slot 43 in the outer end of the shaft 32, the spring normally tending to turn the wheel member in a direction to wind the chain thereon and thereby retract the lever and pedal to their inoperative positions as soon as released. The open medial face of the wheel member and the spring 41 therein are enclosed by a cover 44 held in position by a cotter pin or other means 44' passed through the shaft 32. A stop 45 riveted to the housing 8 limits the movement of the lever 29 and maintains the same spaced from the sprocket wheel 25 of the ratchet device and the outer free end of the lever arm 29 is provided with a web 46 which acts as a guard housing for the sprocket.

With the curved end of the lever arm engaging the stop 45, the stud 33 connecting the chain with the lever arm 29 is in a position disengaging the chain from the sprocket wheel, as illustrated in dotted lines in Figure 1.

To operate the starting device, the user moves the pedal 27 out of its folded position engaging its stop 30 with the stop 31 of the lever arm 29 and steps on the outer end thereof. The initial movement of the pedal engages the chain with the sprocket wheel and further movement rotates the ratchet device, which rotation is imparted to the engine shaft through the pawls 18. As soon as the engine starts turning over its centrifugal force

throws the pawls outwardly disconnecting them from the teeth of the ratchet and the spring 41 retracts the chain 26 winding the same on the wheel member 34. The pedal being pivoted to the lever arm 29 as before described, it is folded to lie close thereto when not in use to prevent possible breakage due to its protruding beyond the engine.

From the foregoing description, taken in connection with the accompanying drawing, it will be readily apparent to those skilled in the art to which an invention of the character described appertains, that I provide a novel and improved starting device for gasoline engines and the like which is ruggedly constructed, has but a few parts and which is positive in its release of the connection between its actuating mechanism and the engine shaft.

What I claim as my invention is:

1. In a starting device for gas engines and the like having a shaft, a member for imparting rotation to the shaft, a flexible drive member engageable with said member, a pivoted lever, means connecting one end of the flexible drive member with the pivoted lever, means connected with the other end of the flexible drive member for yieldably holding said flexible member in an inactive position, movement of said pivoted lever engaging the flexible drive member with the rotation imparting member to turn the same, a foot pedal for moving the pivoted lever, and means pivotally connecting the foot pedal with the lever whereby the same may be folded therealong to an inactive position and extended to a position of use.

2. In a device of the character described, a driven wheel, a flexible driving member adapted to be operatively engaged with the driven wheel, a lever movable to overlie said wheel, means connecting one end of the driving member with the lever whereby the flexible driving member is held out of operative engagement with the driven wheel when the lever is in its normal inactive position, and means for moving said last member to operatively engage the driving member with the driven wheel, continued movement of said last member drawing the driving member over the driven wheel to rotate the same.

3. In a starting device of the character described, a wheel, a member having a portion normally disposed over the periphery of the wheel and covering substantially one side thereof to form a guard housing for the wheel, means for moving said member out of its normal position, and means carried by said member and engageable with the wheel upon movement thereof away from its normal position to rotate the wheel.

4. In a starting device for gas engines and the like, an approximately V-shaped lever member, means pivotally mounting the lever

- member, means movable with the lever member and operable upon an engine carried part to turn the same when the lever member is moved, one side of the approximately V-shaped lever forming a foot pedal adapted to be depressed to move the lever member, and means whereby the foot pedal may be folded against the other side of the lever member and out of the way.
5. In a starting device for engines and the like, a shaft, a drive member mounted on the shaft, means connecting the drive member with the shaft, a sprocket chain engageable with the drive member to actuate the same, means for retracting the sprocket chain, and means whereby the sprocket chain is disengaged from the drive member upon being retracted.
10. 6. A starting device for gas engines and the like including a sprocket chain, a sprocket wheel carried by the engine and adapted to be engaged by the chain and driven thereby upon a pull on the chain, and a drum remote from the sprocket wheel for normally retracting the chain and on which the same is normally wound, and said chain, when retracted, being disengaged from the sprocket wheel.
15. 7. In combination with an engine shaft, a drive member mounted thereon, means connecting the drive member with the shaft, a sprocket chain meshing with the drive member, a drum on which the sprocket chain is normally wound, a foot pedal, means connecting the foot pedal with the chain whereby movement of the foot pedal is imparted to the drive member and to the engine shaft, and means for rewinding the chain on the drum member when the foot lever is released.
20. 8. In a device of the character described, a shaft, a sprocket wheel having a ratchet connection with said shaft, a drive chain normally disconnected from the sprocket wheel, a member to which one end of the drive chain is connected, and means for moving the member to engage the chain with the sprocket wheel, continued movement of said member drawing the chain over the sprocket to rotate the same and with it said shaft.
25. 9. In a starting device of the character described, a sprocket wheel, a member having a goose-neck portion normally positioned over the sprocket wheel and spaced thereover to provide a guard for the sprocket wheel, a drive chain having one end connected with the goose-neck portion of the member, and means for moving the member to engage the chain with the sprocket wheel to rotate it.
30. 10. In a device of the character described, a sprocket wheel, a drive chain normally disconnected from the sprocket wheel, a member to which one end of the drive chain is connected, means for moving the member to engage the chain with the sprocket wheel, continued movement of said member draw-
- ing the chain over the sprocket and rotating it, a drum member with which the other end of the chain is connected, and means at all times tending to wind the chain on the drum member to retract the chain and the first mentioned member to their positions disconnecting the chain from the sprocket wheel.
35. 11. In a starting device of the character described, a wheel, a pivotally mounted member having a goose-neck portion on its outer free end normally overlying the wheel, a rotatably mounted drum member, and a flexible drive member normally disengaged from the wheel and having one end connected with the extreme end of the goose-neck portion of the first member and its other end connected with the drum member to wind thereon, movement of the free end of the first member away from the wheel causing the flexible drive member to engage and rotate the wheel.
40. 12. A starting device for engines and the like, comprising a rotatable drive member, a movably mounted member having a part normally disposed in front of and covering the rotatable drive member to form a guard therefor, and means whereby movement of the second mentioned member away from the drive member imparts rotation to the drive member.
45. 13. In a starting device for engines and the like having a shaft, a drive member connectible with the shaft, a lever arm having a curved end, means pivotally mounting the lever arm whereby its curved end overlies the drive member to form a guard therefor, a sprocket chain having one end connected with the curved end of the lever arm, a drum rotatable about the axis of the pivotal mounting for the lever arm to which the other end of the sprocket chain is connected, and means yieldably tending to wind the sprocket chain on the drum and hold the lever arm in its position overlying the drive member, the connection of the sprocket chain with the curved end of the lever arm being so located that when the lever arm is in said position overlying the drive member, the sprocket chain is disengaged therefrom.
50. 14. In a starting device for engines and the like having a shaft, a drive member connectible with the shaft, a lever arm having a curved end, means pivotally mounting the lever arm for movement to and from a position with its curved end overlying the drive member to form a guard therefor, a drive chain having one end connected with the curved end of the lever arm, a drum about which the other end of the drive chain is wound, the chain being disengaged from the drive member when the lever arm is in its position overlying the drive member, and being engageable therewith to impart rotation thereto upon movement of the lever arm.

away from the drive member, and means connected with the lever arm for imparting said movement to the lever arm upon a direct downward movement of said means.

15. In a starting device for engines and the like having a shaft, a drive member mounted on the shaft, means for connecting the drive member with the shaft, a member having a goose neck portion on its outer free end, means pivotally mounting the member for movement to and from a position at which its goose neck portion overlies the drive member to form a guard therefor, a drive chain having one end connected with the goose neck portion of the member, a retracting drum rotatably mounted adjacent the axis of the pivotal mounting for the member to which the other end of the drive chain is connected, whereby the retracting drum tends to wind the chain thereon and maintain the member in its position overlying the drive member, the drive chain being disengaged from the drive member when the member is in said position, and a foot pedal connected with the member for imparting movement thereto away from the drive member to engage the drive chain with the drive member and rotate the same.

20 In testimony whereof I have hereunto affixed my signature.

25 30 PERRY E. MACK.
